UNITED STATES PATENT OFFICE.

LOUIS E. FREITAG, OF BAKER, OREGON.

SPOON-HANDLE.

1,302,784.

Specification of Letters Patent.

Patented May 6, 1919.

Application filed October 25, 1918. Serial No. 259,693.

To all whom it may concern:

Be it known that I, LOUIS E. FREITAG, a citizen of the United States, residing at Baker, in the county of Baker and State of Oregon, have invented certain new and useful Improvements in Spoon-Handles, of which the following is a specification.

This invention relates in general to spoons and has special reference to the handles thereof.

One object of this invention is the production of a spoon handle which is provided with a removable element which is used for containing various subject matter, such for instance as the photograph of a person while the element may also be initialed for constituting a designating character for the spoon carrying the same.

Another object of this invention is the production of a removable element which consists of a hollow cup in which the subject matter is removably carried while the outer surface of the cup may be initialed, the cup being frictionally or otherwise retained within a suitable aperture formed through the handles, thus causing the contents carried by the cup or the initial or other indicating register thereon to be exposed to view upon opposite sides of the handle.

One practical form of the present invention will be hereinafter described and is illustrated in the drawing in which—

Figure 1 is a front elevation of a spoon, illustrating the forward portion of the removable element.

Fig. 2 is a longitudinal fragmentary section through the end of the spoon handle showing the removable element in section,

Fig. 3 is a transverse section through the spoon handle and element.

Fig. 4 is an enlarged fragmentary sectional view of the engagement of the cup and collar of the removable element.

In the preferred embodiment of the present invention, it will be seen that the removable element is used in connection with an ordinary handle 5 of the spoon 6 and this handle 5 is provided with an aperture 7 formed therethrough, as shown in Figs. 2 and 3.

The removable element consists of a cup formed of a flat back 8 having an annular wall 9 formed therearound and terminating

in an annular flange 10 extending outwardly beyond the wall 9 and being in a plane parallel to the back 8. A retaining collar 11 is substantially the same shape as the wall 9 and this collar fits within the cup, as indicated in Figs. 2 and 3. This collar 11 is flanged as indicated at 12, it being noted that the flange 11 extends beyond both side surfaces of the collar 11 and for this reason bears upon the flange 10 of the cup and also retains the pane of suitable glass 13 in position, since the inner edge of the flange 12 engages in the glass pane 13 as indicated in the figures just referred to. The subject matter indicated at 14 is retained in position by the flange 12 and is protected by the glass pane.

The flanged collar may be pulled from the cup and obviously access will then be permitted to the interior of the cup. The elements 14 upon which the desired subject matter may be carried, such for instance as photographs or flag implements or the like may be placed within the cup, being retained by the back 8. The collar 11 is then forced into the cup, being frictionally engaged by the wall 9 and thus being held against accidental movement. The flange 12 will engage the flange 10 of the cup and will also retain the glass pane 13 and the elements 14 within the cup.

The cup is then slipped into the aperture 7 formed in the spoon handle 5, it being intended to have the cup fitting so snugly within this aperture as to hold the device 90 against displacement. The flange 10 of the cup will bear upon the spoon handle and thus hold the cup from movement entirely through the aperture 7, it being noted that the outer surface of the back 8 of the cup 95 will extend evenly in the outer surface of the handle 5. If desired, a monogram may be engraved upon the flat surface of the back 8 and, as above stated, a photograph may be carried within the cup and retained 100 by the flanged collar.

It is obvious that a device of like nature is of a souvenir-like construction and will be especially appreciated by recipients of the same who would use the spoon and thus 105 have in mind continually the sender of the device who may be in some distant place.

The foregoing description and the drawings have reference to what may be considered the preferred, or approved, form 110

of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent, is:—

- 10 1. An implement including a handle having an opening extending transversely therethrough, a double faced legend element including a flange adjacent one face thereof, said element fitting within said opening, and being viewable from both sides of said handle, said flange bearing upon one surface of said handle for facilitating the positioning of the element within said opening and holding the element from displacement in one direction.
- 15 2. An implement including a handle having an opening extending transversely therethrough, a double faced legend element fitting with said opening and being viewable from both sides of said handle, and means on the element adjacent one face thereof for engaging one surface of said handle, thus facilitating the positioning of the element
- 20
- 25

within said opening and holding the element from displacement in one direction.

3. An implement including a handle having an opening extending transversely therethrough, a double faced legend element consisting of a cup, said cup comprising a flat back having an annular wall upon its periphery, an outwardly extending annular flange on said wall, said cup fitting within said opening and said flange resting upon one surface of said handle, thus holding the element from displacement in one direction, indicating material carried within said cup, a retaining collar engaging the inner surface of the annular wall, said collar having a flange formed upon its outer edge and extending beyond the side surfaces thereof, thus causing the last mentioned flange to fit upon the first mentioned flange and to also engage the indicating material to hold the same within said cup.

In testimony whereof I affix my signature in presence of two witnesses.

LOUIS E. FREITAG.
